(Continued)

Primary Examiner — W. A. Teddy Falloway*(74) Attorney, Agent, or Firm* — Eversheds Sutherland (US) LLP(57) **CLAIM**

The ornamental design for an egg carton, as shown and described.

DESCRIPTION

3. Egg carton
- 3.1 : Top perspective view
- 3.2 : Front plan view
- 3.3 : Back plan view
- 3.4 : First side plan view
- 3.5 : Second side plan view
- 3.6 : Top plan view
- 3.7 : Bottom plan view

The broken lines shown illustrate portions of the egg carton and form no part of the claimed design.
